(57) **CLAIM**

The ornamental design for a visualization trocar, as shown and described.

DESCRIPTION

FIG. 1 is a perspective view of a visualization trocar according to the present invention;

FIG. 2 is a lateral perspective view of the visualization trocar of FIG. 1;

FIG. 3 is a rear perspective view of the visualization trocar of FIG. 1;

FIG. 4 is a side elevational view of the visualization trocar of FIG. 1;

FIG. 5 is a top plan view of the visualization trocar of FIG. 1; FIG. 6 is a front end view of the visualization trocar of FIG. 1; FIG. 7 is a rear end view of the visualization trocar of FIG. 1; FIG. 8 is a perspective view of a visualization trocar according to a second embodiment of the present invention.

FIG. 9 is a lateral perspective view of the visualization trocar of FIG. 8;

FIG. 10 is a rear perspective view of the visualization trocar of FIG. 8;

FIG. 11 is a side elevational view of the visualization trocar of FIG. 8;

FIG. 12 is a top plan view of the visualization trocar of FIG. 8;

FIG. 13 is a front end view of the visualization trocar of FIG. 8; and,

FIG. 14 is a rear end view of the visualization trocar of FIG. 8.

The stippling shown in FIGS. 8-14 indicates opacity of the distal end portion of the claimed design.
